UNITED STATES PATENT OFFICE

JOHN OSCAR CARLSON, OF YOUNGSTOWN, OHIO, ASSIGNOR TO TRUSCON STEEL COMPANY, OF YOUNGSTOWN, OHIO, A CORPORATION OF MICHIGAN

WEATHER STRIP FOR METAL SASH

Application filed May 15, 1929. Serial No. 363,171.

This invention relates to an improved weatherstrip particularly adapted for use in connection with metal sash.

The general object of the invention is to provide a weatherstrip constructed to provide an efficient, free sliding weatherproof joint between a sash and a frame, and to prevent rattle and lateral movement of the sash within the frame.

More particularly it is an object of the invention to provide a novel means of securing a weatherstrip to a sash so as to insure against loosening or loss of the strip from the sash.

Another particular object of the invention is to provide the present weatherstrip with a novel rib formation to limit lateral movement of the sash within the frame.

With the foregoing and other objects in view, the invention consists in the novel features of construction, combination and arrangement of parts as will be hereinafter more fully described, illustrated in the accompanying drawings and defined in the appended claims.

In the drawings, wherein like characters of reference denote corresponding parts in the different views:

Fig. 1 is a fragmentary front elevation of a metal window construction having the present weatherstrip embodied therein.

Fig. 2 is a horizontal section on the line 2—2 of Fig. 1.

Fig. 3 is a perspective view of a fragment of one form of weatherstrip embodying the present improvements.

Fig. 4 is a perspective view of a fragment of another form of weatherstrip embodying the present improvements; and

Fig. 5 is a detail sectional view showing the manner of mounting the strip of Fig. 5 upon a sash.

Referring to the drawings in detail, A designates, generally, a metal window frame, and B a metal sash slideable therein. For convenience the frame A and the sash B herein illustrated are of a well known commercial type, but, as will hereinafter become more fully apparent, they may be of any desired specific construction so long as the frame

50 A is inclusive of a slot 10 to receive a stile

of the sash, and the sash is inclusive of a stile 12 slidably disposed within said slot, these being the only essentials, as regards the frame and sash, in so far as the present improvements are concerned.

The present weatherstrip 14 is formed from an originally flat strip of thin, resilient metal which is rolled or otherwise shaped to provide, in cross section, a U-shaped formation 16 extending along one side thereof and 55 a bead 18 extending along the opposite side thereof.

The formation 16 consists of a lip 20 disposed parallel to and overlying an adjacent portion of the strip 14 in spaced relation 65 thereto, and a web 22 connecting said lip with the body portion 14 of the strip, said U-shaped formation thus being disposed to one side of the plane of the body portion of the strip as is manifest. The bead 18 on the 70 other hand is disposed upon the opposite side of the plane of the body portion of the strip and is formed by bending a portion of the strip first outwardly, as at 24, and then inwardly as at 26, said inwardly bent portion 75 26 preferably but not necessarily having its terminal or marginal portion bent upon itself to provide a stiffening flange 28.

In accordance with the invention the body portion 14 of the strip, from a line substantially overlying the free edge of the lip 20 to the side thereof provided with the bead 18, has a normal flexure in an outward direction with respect to the lip 20 for a purpose which will presently appear.

The distance between the adjacent faces of the body portion and the lip 20 of the strip 14 is approximately equal to the thickness of the stile 12 of the sash to which the strip is to be applied. Thus, the marginal portion of the stile is adapted to be received within the U-shaped formation 16 and when it is so received the body portion of the strip is disposed in overlying relation to one side face of the stile as clearly illustrated in the drawings, that portion of the strip near the bead 18 being disposed in spaced relation to the stile due to the aforesaid normal flexure of the strip, as is manifest.

With the strip 14 mounted on the stile 12 100

as described, and with the stile 12 disposed within the slot 10 of the frame A as illustrated, i. e. with the rib 18 disposed upon the sash side of the frame wall having the slot 10 and the formation 16 disposed upon the other side of said frame wall, and the flexed portion of the strip 14 bearing against one edge of the slot 10, it follows that the slot 10 is weather sealed, that the sash is held against rattling, and that lateral movement of the sash is limited by cooperation of the bead 18 with the side wall of the frame at the edge of the slot 10.

It is quite desirable to provide simple, efficient means to positively retain the strip 14 on the stile 12 and in accordance with the present invention this result may be accomplished either as shown in Figs. 2 and 3 or as shown in Figs. 4 and 5 of the drawings.

20 As illustrated in Fig. 2, a groove or channel 30 is formed in the face of the stile against which the lip 20 is disposed, and an inturned flange 32 on the free or marginal edge portion of the lip 20 is directed into this groove or channel. On the other hand, as illustrated in Fig. 5 of the drawings, a groove or channel 34 is formed in the face of the stile 12 against which the body portion of the strip 14 is disposed, and the said body portion of the strip 30 has formed therein a rib 36 which is disposed within said groove or channel. Either of these constructions provides an efficient interlock between the weatherstrip and the sash stile insuring against loosening or loss of the strip from the stile.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

45 I claim:

1. A weatherstrip having a U-shaped formation adapted to embrace the outer marginal portion of a sash stile, and an inwardly directed projection on a wall of said U-shaped formation adapted to be received within a recess in the sash stile to interlock the strip with the sash, the said sash stile being continuously straight transversely within the limits of the inner and outer side edges of the weatherstrip.

2. A weatherstrip having a formation to receive and embrace a marginal portion of a sash stile, and an inwardly directed rib on a wall of said formation adapted to be received within a groove in the sash stile to interlock the strip with the sash, the said sash stile being continuously straight transversely within the limits of the inner and outer side edges of the weatherstrip.

65 3. A weatherstrip having a U-shaped for-

mation to receive and embrace a marginal portion of a sash stile, said formation being inclusive of a lip for engagement with one side face of the sash stile, and an inwardly directed marginal flange on said lip adapted to be received within a groove in the sash stile to interlock the strip with the sash, the said sash stile being continuously straight transversely within the limits of the inner and outer side edges of the weatherstrip.

4. A weatherstrip having a U-shaped formation to receive and embrace a marginal portion of a sash stile, and interlocking formations on said strip and said stile, respectively, preventing edgewise lateral movement of the strip with respect to the stile, the said sash stile being continuously straight transversely within the limits of the inner and outer side edges of the weatherstrip.

5. A weatherstrip having a U-shaped formation to receive and embrace a marginal portion of a sash stile, one of the side walls of said U-shaped formation having an inwardly directed projection intermediate its ends adapted to be received within a recess in the adjacent face of the sash stile to interlock the strip with the sash, the said sash stile being continuously straight transversely within the limits of the inner and outer side edges of the weatherstrip.

In testimony whereof I hereunto affix my signature.

JOHN OSCAR CARLSON.
